United States Patent Office

Des. 192,655
Patented Apr. 24, 1962

192,655

BOTTLE

Robert E. Sarafan, San Francisco, Calif., assignor to Flexible Plastics Corporation, San Francisco, Calif.

Filed Oct. 16, 1961, Ser. No. 67,114

Term of patent 14 years

(Cl. D58—5)

FIG. 2.

FIG. 1.

FIG. 3.

FIG. 1 is a perspective view taken from the bottom of a bottle, showing my new design.

FIG. 2 is a top plan thereof.

FIG. 3 is a side elevational view thereof.

I claim:
The ornamental design for a bottle, as shown.
